UNITED STATES PATENT OFFICE.

WILLIAM AUGUSTINE SPAIN, OF LONDON, ENGLAND.

ROWING MACHINE.

Application filed May 15, 1928, Serial No. 277,803, and in Great Britain December 7, 1927.

This invention relates to rowing machines for practising rowing or for physical training purposes and has for an object to provide a simple and inexpensive construction which 5 can be quickly assembled or taken apart and which when disassembled occupies a minimum of space.

The improved rowing machine in accordance with the invention comprises a pair of 10 standards or uprights between which is adapted to be supported a guide bar or rod on which are slidably mounted a pair of foot rests movable by the feet against the action of elastic tension means connected thereto 15 and to one of the uprights so as to offer a resistance to movement in one direction, and a handle bar taking the place of oars and connected by elastic tension means with the same upright so as to offer the necessary resistance 20 to movement of the handle bar. A box or case in which the disassembled rowing machine may be carried from place to place may serve as the seat for the person using the machine.

In one embodiment of the invention the 25 uprights, which are preferably of substantially inverted U shape, support a guide bar of tubular form or of rectangular section and the foot-rests consist of a pair of pedals like bicycle pedals connected by a crosshead or 30 bracket embracing such guide bar. The necessary resistance to movement of these 35 pedals by the feet is presented by extensible members constituted of rubber or the like and formed at the ends with eyelets to engage hooks attached to the crosshead and to engage 40 the legs of the uprights. The handle bar is connected by a bracket with a hook to which extensible members are connected such extensible members being connected at their 45 other ends by a hook to a wire rope or the like guided over a pulley mounted on the guide bar, such wire rope terminating in a hook adapted to engage extensible members which are anchored to the uprights suitably adjacent 50 to the extensible members to which the foot rests are attached. There are thus provided for the handle bar two sets of extensible members allowing the necessary movement of the handle.

55 The box provided for transporting the parts in disassembled condition is preferably provided with compartments for the various parts, the stretching members being attached to hooks in the box and serving to retain the other parts in position therein.

In the accompanying drawings, Fig. 1 is a

perspective view of a rowing machine according to the invention; the machine being shown assembled and resting on top of its containing box or case. Fig. 2 is a perspective view showing the machine and box in position ready for use. Fig. 3 is a perspective view showing the machine disassembled and accommodated within its containing case. Fig. 4 is a plan view showing a modified construction.

The rowing machine shown comprises a pair of inverted substantially U shaped standards 1, 2 each of which is connectible to one end of and adapted to support a rectangular 70 guide bar 3 on which is slidably mounted a cross head 4 sustaining a pair of foot rests constituted by a pair of pedals 5 extending transversely of the guide bar 3.

The legs of the U shaped standard 1 are 75 splayed and are equipped at their terminal ends with bearer blocks 6 adapted to rest on the floor or the like, the legs of the standard 2 are engageable in socket members 7 secured to one end of the box case 8 when the machine 80 is ready for use as shown in Fig. 2. The case 8 forms a seat for the operator and is equipped on its upper face with a mat 9, the operator sitting on the mat with his legs astride the bar 3 and his feet engaging the 85 pedals 5.

The crosshead 4 and pedals 5 carried thereby are movable in one direction by the operator's feet along the guide bar 3 against the action of elastic rubber members 10 formed 90 at both ends with eyelets 10' connected at one end to hooks 11 formed on the crosshead 4 and anchored at the other end on the U standard 2.

A handle bar 12 taking the place of oars 95 carries a bracket 12' provided with a hook 12' connectible to elastic rubber members having connecting eyelets 13', the other ends of which members are engaged by a hook 14' on one end of a wire rope 14 or the like guided 100 over a pulley 15 journalled on the guide bar 3 at the outer end thereof, the wire rope 14 passing backwardly beneath the guide bar 3 and terminating at its rear end in a hook 14' 105 engaging eyelets 16 on the adjacent ends of elastic rubber members 17, the eyelets 16' at the other ends of which are anchored on the U standard 2.

A safety chain 18 adapted to be anchored to the standard 1 and connected to the hook 14' on the wire rope 14 prevents injury to the operator in the event of breakage of the rope.

As shown in Fig. 3 the elastic members are engageable with hooks secured to the inner walls of the box 8 whereby to hold the disassembled members of the machine in position 5 within the box, the lid of which is divided into compartments.

In the modified construction shown in Fig. 4 the guide bar 3 is replaced by spaced tubular guides 19 which penetrate the pedal-supporting crosshead 4, said crosshead being 10 slidable thereon as before.

I claim:

1. A rowing machine comprising, in combination a pair of uprights, a guide bar sustained by said uprights, foot-rests movable along said guide-bar, elastic tension means connected at one end to said foot-rests and anchored at the opposite end, a handle bar, and a tension member including elastic components connected at one end to said handle bar and anchored at its opposite end externally of the foot-rests, said tension member extending partly along said guide bar.

2. A rowing machine comprising, in combination, a pair of uprights a guide bar sustained by said uprights, foot-rests movable along said guide-bar, elastic tension means connected at one end to said foot-rests and anchored at the opposite end to one of said 30 uprights, a handle bar, and a tension member including elastic components connected at one end to said handle bar and anchored at

its opposite end to said last mentioned upright, said tension member extending partly along said guide bar.

3. A rowing machine comprising, in combination a pair of uprights, a guide bar sustained by said uprights, a pulley on the guide-bar, foot-rests movable along said guide-bar, elastic tension means connected at one end to 40 said foot-rests and anchored at the opposite end, a handle bar, and a tension member including elastic components connected at one end to said handle bar, and anchored at its opposite end externally of the foot-rests, said 45 member passing around said pulley and extending partly along said guide bar.

4. A rowing machine comprising, in combination, a seat-presenting box having sockets at one end, a pair of uprights, one engaging 50 said sockets, a guide-bar sustained by said uprights, foot-rests movable along said guide-bar, elastic tension means connected at one end to said foot-rests and anchored at the opposite end to the last mentioned upright, a handle bar, and a tension member including 55 elastic components connected at one end to said handle bar and anchored at its opposite end to said last mentioned upright, said tension member extending partly along said 60 guide-bar.

In testimony whereof I have signed my name to this specification.

WILLIAM AUGUSTINE SPAIN.
